F. E. CROTTO,
WELL WASHING DEVICE,
APPLICATION FILED JAN. 31, 1921.

1,401,464.

Patented Dec. 27, 1921.

UNITED STATES PATENT OFFICE.

FRANK E. CROTTO, OF DALLAS, TEXAS, ASSIGNOR TO RECLAMATION OIL PRODUCING ASSOCIATION.

WELL-WASHING DEVICE.

1,401,464.

Specification of Letters Patent. Patented Dec. 27, 1921.

Application filed January 31, 1921. Serial No. 441,257.

To all whom it may concern:

Be it known that I, FRANK E. CROTTO, a citizen of the United States, residing at Dallas, in the county of Dallas and State of Texas, have invented certain new and useful Improvements in Well-Washing Devices, of which the following is a specification.

This invention has to do with well washing devices.

10 The object of the invention is to provide a washing device for Artesian wells without screens and in which an enlarged pocket is formed at the bottom of the well. A particular feature of the invention is the provision of outwardly swinging nozzles arranged to be swung outwardly by the pressure of the washing fluid and automatically retracted when the pressure is cut off. Another object is to provide a plurality of nozzles, 20 whereby the washing will be more expeditiously and more evenly carried out.

A construction designed to carry out the invention will be hereinafter described together with other features of the invention.

25 The invention will be more readily understood from a reading of the following specification and by reference to the accompanying drawings, in which an example of the invention is shown and wherein:

30 Figure 1 is an elevation of a device constructed in accordance with my invention, the nozzles being extended,

Fig. 2 is a vertical sectional view of the upper portion of the device,

35 Fig. 3 is a vertical sectional view of the lower portion of the device,

Fig. 4 is a cross-sectional detail on the line 4—4 of Fig. 2,

40 Fig. 5 is a cross-sectional view taken on the line 5—5 of Fig. 3, and

Fig. 6 is a cross-sectional view taken on the line 6—6 of Fig. 2.

In the drawings the numeral 10 designates a tubular housing having a guide plug

45 11 screwed into its lower end. The upper end of the housing is internally screw threaded and is mounted on the lower end of a head 12 into the upper end of which the lower end of a barrel 13 is screwed.

50 The upper end of the barrel is screwed into a reducing coupling 14 which is screwed onto the lower end of a sleeve 15. The upper end of the sleeve is secured into a second reducing coupling 16, which receives

the lower end of the string of pipe 17, 55 through which the cleaning fluid is supplied.

The head has three depending nipples 18, although the number may vary, to which hose couplings 19 are attached. A short flexible tube or hose 20 is secured to each coupling 60 19 and has its lower end connected with a nozzle 21 by a second coupling 22. Vertical openings or slots 23 in the side of the housing extend from the head to a point just below the nozzle. Each nozzle has its 65 lower end beveled and its bore directed therethrough so as to expel the cleaning fluid outwardly. The fluid from the barrel 13 passes through ports 12' in the head. The nozzles and hose are swung outwardly 70 through the slots 23, but all parts are normally confined within the diameter of the housing, as is shown in Fig. 3.

An actuating rod 24 extends axially through the housing, head, barrel and sleeve. 75 The head has a central upstanding nipple 25 through which the rod slides. The lower end of the rod is confined in a guide tube 26 screwed into the plug 11. A cross-head 27 is fastened on the rod by a pin 28 within 80 the housing and is provided with recesses 29 extending inwardly from its outer edge, as is best shown in Fig. 5. The lower portion of each nozzle is pivoted between the lower ends of a pair of links 30 having their upper 85 ends pivoted to the sides of the recesses 29. It will be seen that when the cross-head is moved downward by the rod, the links will swing the nozzles outwardly and at an inclination as is shown in Fig. 1. 90

Within the barrel 13 a flanged collar 31 is fastened on the rod 24. A coiled spring 32 surrounds the rod and has its lower end engaging about the nipple 25; while its upper end supports the collar 31. A second coiled 95 spring 33 has its lower end engaged about the collar 31 and its upper end fastened around a boss 34 on the underside of a wing valve 35 within the sleeve 15. The spring 33 is considerably longer and of greater tension than the spring 32. The valve 35 is free to slide on the rod. 100

In operating the device it is lowered into the well until the housing 10 is within the oil sand pocket. The cleaning fluid, preferably water, is pumped into the line of pipe 17 so as to exert a pressure on the valve 35, whereby it is displaced down-

wardly. The light tension spring 32 will yield and the spring 33 will thus force the collar 31 downwardly, without yielding itself. The collar 31 will move the rod 24 downwardly whereby the links 30 will swing the nozzles 21 outwardly. The nozzles will be swung outwardly to their limit and the spring 32 will be compressed before the spring 33 will yield.

10 The sleeve 15 is of such length that the lower end of the valve will not pass below the same until the nozzles are fully expanded and the spring 33 under compression. When the spring 33 yields the lower end of the valve 35 will be carried down through the coupling 14 and into the upper end, but never far enough to withdraw its upper end from the sleeve. When the valve enters the coupling 14 the fluid will pass around said 15 valve and down through the barrel 13, ports 12' and hose 20 to the nozzles 21. When the nozzles are extended their beveled ends will direct the jets of cleaning fluid against the sides of the pocket and cleanse the same. 20 By employing three nozzles a greater area is washed at a time and the work is more evenly done than where only a single nozzle is used. The pipe 17 may be rotated so that the entire circumference of the 25 pocket will be washed, after which the housing is raised to wash at a higher level. When the fluid is cut off the springs expand and return the parts to their normal position. 30 Various changes may be made in the dimensions and construction and modifications may be made without departing from the spirit of the invention.

What I claim, is:

1. In a well cleaning device, a housing 40 having an opening, a nozzle within the housing arranged to swing outwardly through the opening thereof, tubular connections for supplying fluid to the nozzle, a valve in one of the connections controlling the supply of fluid, and means actuated by the pressure of the fluid for causing the nozzle to be swung outward prior to the operation of the valve to supply fluid to the said nozzle.
2. In a well cleaning device, a housing 50 having an opening, a nozzle within the housing arranged to swing outwardly through the opening thereof, tubular connections for supplying fluid to the nozzle, a valve in one of the connections controlling the supply of fluid, and means actuated by the pressure of the fluid for causing the nozzle to be swung

outward prior to the operation of the valve to supply fluid to the said nozzle, said means acting to retract the nozzle when the pressure of the fluid is relieved. 60

3. In a well cleaning device, a housing having an opening, a nozzle pivoted within the housing, means for swinging the nozzle outwardly through the opening of the housing, tubular connections for supplying a fluid under pressure to the nozzle, a valve in one of the connections controlling the supply of fluid, and means actuated by the pressure of the fluid for operating the nozzle swinging means prior to the operation of the valve to supply fluid to the nozzle. 65

4. In a well cleaning device, a pivoted nozzle, means for swinging the nozzle outwardly, tubular connections for supplying a fluid under pressure to the nozzle, means for controlling the passage of fluid through the connections to the nozzle, and means actuated by the pressure of the fluid for operating the nozzle swinging means prior to the operation of the controlling means to permit the passage of the fluid to the nozzle. 70

5. In a well cleaning device, a pivoted nozzle, means for swinging the nozzle outwardly, tubular connections for supplying a fluid under pressure to the nozzle, means for controlling the passage of fluid through the connections to the nozzle, means actuated by the pressure of the fluid for operating the nozzle swinging means prior to the operation of the controlling means to permit the passage of the fluid to the nozzle, and means for restoring the parts to their normal position when the pressure of the fluid is relieved. 85

6. In a well cleaning device, a housing having vertical openings, tubular connections attached to the housing, nozzles pivoted in the housing and connected with the tubular connections, a sliding rod mounted 100 in the housing and connections, swinging elements connected with the rod and the nozzles for swinging the nozzles outwardly through the openings of housing, a resilient support for the rod, and a valve sustained 105 on the rod for controlling the supply of a fluid under pressure to the nozzles, said valve acting to force the rod downward against the tension of the resilient support and operate the nozzle swinging elements 110 prior to the passage of the fluid to the nozzles.

In testimony whereof I affix my signature.
FRANK E. CROTTO
